UNITED STATES PATENT OFFICE.

JAKOB SULSER, OF BASEL, SWITZERLAND, ASSIGNOR TO THE SOCIETY ELEKTRIZITATS-
WERK LONZA, OF GAMPEN AND BASEL, SWITZERLAND.

PLASTIC COMPOSITION.

No Drawing.

Application filed October 31, 1922. Serial No. 598,201.

To all whom it may concern:

Be it known that I, JAKOB SULSER, a citizen of the Swiss Republic, and resident of Basel, Switzerland, have invented a new and useful Plastic Composition, of which the following is a full, clear, and exact specification.

In the manufacture of a number of plastic compositions for use as floor coverings, wall coverings and so forth, additions of cork meal, wood meal or saw-dust or like light and porous materials are employed for loosening the mass. So for example linoleum as is well known is made by kneading together the linoleum cement with cork meal or wood meal, and lincrusta coverings are similarly made of linoxyn (oxidized linolein) with wood meal; in other materials used for floor or wall coverings other binding materials are employed, such as cement or the like with mineral fillings to which a greater or less proportion of wood meal is added according to the use for which the material is intended. Such materials do not well withstand prolonged exposure to dampness; for the reason that cork and wood easily absorb moisture and are then liable to rot.

It has now been discovered that these additions of wood, turf, cork and so forth may with advantage be wholly or partially replaced by cuprene, and linoleums produced with cuprene are resistant to moisture and other chemical attacks, for cuprene withstands most chemical agents and also is not affected by water. By cuprene I designate the products of polymerization of acetylene resulting from the condensation of acetylene in the presence of copper or through dark electric discharges. These condensation products are well known (see Berliner Be-richte 32, 2381, and 55, 267, Comptes Ren-

dus, Vol. 130, page 250, and Vol. 122, page 1240, etc.). They constitute a corklike mass which is substantially unalterable and incapable of being wet. The production of linoleum or of the lincrusta material is not different from the usual method except that instead of kneading the linoleum cement with cork meal or wood meal, it is kneaded with finely ground cuprene or with cuprene produced in an exceedingly fine grained form; and the mass thus formed is then pressed upon paper or jute in known manner.

It is important to state that the cuprene serves only as an addition or so-called filling for externally uniform plastic materials produced by intimately kneading the cuprene with a binding material such for instance, as linoleum, lincrusta and so forth; further, that the plastic materials produced from cuprene have the above mentioned advantages as compared with those made from wood or cork.

What I claim is:

1. A plastic composition composed of an intimate mixture of a linoleum cement with cuprene as filling material, substantially as and for the purpose described.

2. A plastic composition composed of an intimate mixture of a linoleum cement with finely divided cuprene as filling material, substantially as and for the purpose described.

In witness whereof I have hereunto signed my name this 16th day of October, 1922, in the presence of two subscribing witnesses.

JAKOB SULSER.

Witnesses:

AMAND BRAUER,
MADELEINE SPENGLER.
